UNITED STATES PATENT OFFICE.

WALTER M. CONGER, OF NEWARK, NEW JERSEY.

IMPROVEMENT IN DUST-PANS.

Specification forming part of Letters Patent No. 129,935, dated July 30, 1872.

Specification describing a certain Improvement in Combined Dust Pan and Brush, invented by WALTER M. CONGER, of Newark, Essex county, New Jersey.

The importance of providing means for attaching together a dust-pan and the brush adapted to be used with it, is generally recognized.

I will describe what I consider the best means of carrying out the invention. I attach to the upper side of the handle a flat and elastic hook of sheet metal, and fix in the back of the brush a correspondingly long staple. The staple is not appreciably in the way when the brush is in use. Neither is the hook objectionable in the use of the dust-pan. A simple movement engages the staple of the brush with the spring-hook, and leaves the parts very effectually combined, with the brush mainly in and over the capacious body of the dust-pan.

The accompanying drawing forms a part of this specification.

Figure 1 is a section in the line S S in the other figure. Fig. 2 is a plan view.

Similar letters of reference indicate like parts in both the figures.

A is the body of the dust-pan, and A' the handle thereof. I solder on the upper surface of the handle A' a broad hook, m, of spring-brass. The brush D may be of the ordinary construction, with a wood body. A staple, d, is driven strongly therein, adapted to receive the broad hook m, which latter is made sufficiently close to spring together a little and retain it.

The brush and pan are used in the ordinary

manner. After each use the staple d is engaged with the hook m, and the two may be hung up together by the ordinary ring in the handle. The breadth of the hook m and the corresponding form of the wide staple d tend to guard against any twisting motion of the one part, relatively to the other when they are engaged. The flat form of the hook m enables it to develop a considerable elasticity without being weak, and this allows the hook to cling upon the staple with such tenacity as to avoid their being shaken apart by any ordinary motions.

This invention may be applied to the form of dust-pan described in my patent dated February 6, 1872, in which there is a hood extending up and forward from the edge of the back proper and partially covering the body of the dust-pan. It may be accomplished by fixing the hook m on the under side of the front edge of such high back or partial overhanging hood. The brush will, in either case, be held with its main body in the body of the dust-pan, and with a portion of its handle extending beyond the side.

I claim as my invention—

The hook-fastening m fixed on the pan A A', adapted to engage with the corresponding staple d fixed on the brush D and serve together, as herein specified.

In testimony whereof I have hereunto set my hand this 9th day of April, 1872, in the presence of two subscribing witnesses.

WALTER M. CONGER,
